Primary Examiner — Paula Allen Greene*(74) Attorney, Agent, or Firm* — Amin, Turocy & Watson, LLP(57) **CLAIM**

The ornamental design for an earphone, as shown and described.

DESCRIPTION

FIG. 1 is a first perspective view of an earphone.
 FIG. 2 is a second perspective view thereof.
 FIG. 3 is a front elevation view thereof.
 FIG. 4 is a rear elevation view thereof.
 FIG. 5 is a top plan view thereof.
 FIG. 6 is a bottom plan view thereof.
 FIG. 7 is a right side elevation view thereof; and,
 FIG. 8 is a left side elevation view thereof.
 The broken lines shown in the drawings illustrate portions of
 the earphone that form no part of the claimed design.
